UNITED STATES PATENT OFFICE.

SAMUEL K. DENNIS, OF WEST PULLMAN, ILLINOIS, ASSIGNOR TO THE PLANO MANUFACTURING COMPANY, OF CHICAGO, ILLINOIS.

DESIGN FOR A MAIN FRAME FOR HEADERS.

SPECIFICATION forming part of Design No. 26,745, dated March 9, 1897.

Application filed November 16, 1896. Serial No. 612,373. Term of patent 14 years.

To all whom it may concern:

Be it known that I, SAMUEL K. DENNIS, a citizen of the United States, residing at West Pullman, in the county of Cook and State of Illinois, have invented and produced a new and original Design for Main Frames for Headers, of which the following is a specification, reference being had to the accompanying drawings, in which—

10 Figure 1 is a plan view showing a main frame constructed according to my design, and Fig. 2 is a perspective view of the same.

The essential features of my main frame F, in the form and shape of which my new and 15 original design lies, comprise a looped or approximately U-shaped bar F', consisting of the parallel side bars f' and the connected

or joining end bar f². Leading outward from and extending parallel with the connected or joining end bar f² is the brace-bar f³, which is bent slightly inward at F² and extends some distance therefrom to form the inwardly-inclined bar f⁴, which is bent or curved near its end to form the short arm f⁵, said arm being parallel with the bars f' f'. 25

What I claim, and desire to secure by Letters Patent, is—

The design for a main frame for headers herein shown and described.

SAMUEL K. DENNIS.
